UNITED STATES PATENT OFFICE.

JOHN MARSTON, 3d, OF LOWER MERION TOWNSHIP, MONTGOMERY COUNTY, PENNSYLVANIA.

INTERLOCKING SWITCH AND SIGNAL DEVICE FOR RAILROADS.

SPECIFICATION forming part of Letters Patent No. 240,153, dated April 12, 1881.

Application filed February 1, 1881. (No model.)

To all whom it may concern:

Be it known that I, JOHN MARSTON, 3d, a citizen of the United States, residing in Lower Merion township, Montgomery county, Pennsylvania, have invented certain Improvements 5 in Interlocking Switch and Signal Devices for Railroads, of which the following is a specification.

My invention relates to certain improvements 10 in the construction of interlocking switch and signal devices for railroads, the objects of my improvements being to simplify and cheapen the mechanism employed, and to insure a more direct action than usual of the switch and 15 signal levers upon each other.

In the accompanying drawings, Figure 1 is a side view of a switch-stand with switch and signal operating levers constructed according 20 to my invention; Fig. 2, a diagram showing the position of the rails and signals when the levers are adjusted as in Fig. 1; Fig. 3, a side view of the switch-stand, with the switch and signal levers in different positions from those shown in Fig. 1; and Fig. 4, a diagram showing 25 the position of the rails and signals when the levers are adjusted as in Fig. 3.

A represents the switch-stand, to which is pivoted the switch-operating lever B, the short arm of which is connected to the switch-rails, 30 as usual, and is enlarged so as to present three segmental faces, *a*, *b*, and *d*.

D and E are two levers hung to the stand A, and connected, by means of the ordinary arrangement of pulleys, levers, and cords or wires, to semaphore or other signals, the lever D being connected to a signal, *x*, on the main line of track, and the lever E to a signal, *y*, on the siding or branch line. The short arm of the lever D has a laterally-projecting pin, *e*, 35 and the short arm of the lever E has a similar pin, *f*, these pins acting, in conjunction with the segmental faces of the switch-lever B, to effect the locking both of the switch and signal levers, in the manner which I will now proceed to describe.

When the various levers are adjusted to the 45 positions shown in Fig. 1 the switch-rails are set in line with the siding or branch track, as in Fig. 2, the branch-line signal *y*, controlled

by the lever E, is set at the position of safety, 50 and the main-line signal *x*, controlled by the lever D, is set so as to indicate danger. So long as the signal *y*, controlled by the lever E, remains in the position indicating safety the switch-rails are locked in the position shown 55 in Fig. 2, for the pin *f* of the lever E bears against the face *d* of the lever B, and effectually prevents any movement of said lever tending to change the position of the switch-rails. At the same time the main-line signal, controlled, by the lever D, is locked in the position of "danger," owing to the fact that said lever D is prevented from moving by the contact of its pin *e* with the face *b* of the lever B. Any movement of the lever E in the direction 60 of the arrow, so as to unlock the switch-lever, will move the branch-line signal from the safety position, and the switch-lever B is not free from the control of said lever E until the latter has been moved in the direction of the 65 arrow to its fullest extent, as in Fig. 3, by which time the branch-line signal *y* has been set to the position indicating danger. The switch-lever B is then free to be moved in the direction of the arrow from the position shown 70 in Fig. 1 to that shown in Fig. 3, this movement accomplishing three results—namely, the setting of the switch-rails to accord with the main line, the locking of the branch-line signal *y* by the contact of the face *b* of the switch-lever with the pin *f* of the lever E, and the releasing of the lever D by bringing into line 75 with the pin *e* of the latter the concentric face *a* of the switch-lever. The moment the lever D, however, is moved in the direction of the 80 arrow, Fig. 1, to change the main-line signal from the danger position to the safety position, the pin *e*, by contact with the face *a* of the switch-lever, locks the latter in position, and the switch-rails are secured.

It will thus be seen that when the switch-rails are set in line with the siding or branch track the switch-lever is held, and the main-track signal *x* locked in the danger position by the lever E, and this state of affairs continues as long as the branch-track signal *y* is in any other than the danger position, and the branch-track signal and switch-lever are simi- 85 90 95

larly locked by the lever D when the switch-rails are adjusted in line with the main track.

Independent of the absolute safety thus attained, the main advantages of my invention are the simplicity and fewness of the parts employed, the compactness with which the parts are arranged, and the direct action of the parts upon each other—that is to say, without the intervention of the usual cams, bars, 10 levers, and springs.

I have shown the switch-lever combined with levers for operating both main and side track signals; but said switch-lever may be combined with a main-track signal-lever or a side-track 15 signal only, if desired; and where a single switch requires to be combined with three signal-operating levers the switch-lever may be secured to a rock-shaft carrying a segmental arm similar to the short arm of the main switch-lever, and the pin of the third signal-lever may 20 act in connection with this additional arm of the switch-lever. In some cases, also, the signal-lever may have enlarged arms with segmental faces, and the switch-lever may carry a pin or 25 pins for engaging with said segmental faces,

in place of the reverse arrangement before shown and described.

I claim as my invention—

1. In an interlocking switch and signal device having a switch-lever and a signal-lever 30 hung to a stand or support, the within-described locking mechanism, comprising an enlarged arm of one of said levers and a pin or projection on the other lever for engaging with the edge of said enlarged arm, all substantially as set forth.

2. The combination of the switch-lever B, the short arm of which has segmental faces a, b, and d, with the signal-levers D and E, having pins or projections for engaging with said segmental faces of the lever B, whereby both switch-levers and signal-levers are locked in position, as set forth.

In testimony whereof I have signed my name to this specification in the presence of two sub- 45 scribing witnesses.

JOHN MARSTON, 3D.
